UNITED STATES PATENT OFFICE.

WILLIAM SCHWEITZER AND HARRY H. LABADIE, OF CHICAGO, ILLINOIS.

PORTABLE DISPLAY-STAND.

1,089,349.

Specification of Letters Patent. Patented Mar. 3, 1914.

Application filed August 9, 1913. Serial No. 783,920.

To all whom it may concern:

Be it known that we, WILLIAM SCHWEITZER and HARRY H. LABADIE, citizens of the United States, and residents of the city of Chicago, in the county of Cook and State of Illinois, have jointly invented certain new and useful Improvements in Portable Display-Stands; and we do hereby declare that the following description of our said invention, taken in connection with the accompanying sheet of drawings, forms a full, clear, and exact specification, which will enable others skilled in the art to which our said invention appertains to make and use the same.

This invention has general reference to improvements in portable display stands, and it consists, essentially, in the novel and peculiar combination of parts and details of construction, as hereinafter first fully set forth and described, and then pointed out in the claims.

In the drawings already referred to, which serve to illustrate our said invention more fully, Figure 1 is a perspective view thereof. Fig. 2 is an end elevation of the device as collapsed. Fig. 3 is an inside elevation of the collapsing means.

Like parts are indicated by corresponding symbols and characters of reference in all the figures of the drawings.

The old fashioned method of effecting sales by the exposition of samples in original packages, containers, or the like is rapidly becoming obsolete. For instance, in crackers it has been the practice of displaying a number of cartons of each of the various kinds in the show window or upon the counter. Again in candies practically the same procedure has been followed, *i. e.* that of opening a number of boxes and exposing the contents to view. Coffees, cereals, dried fruits, and other analogous articles have been similarly displayed from time immemorial. An effective display requires room, time, and taste; elements not always present. Therefore, the hodge-podge appearance of stock in the average store is a familiar one.

It is the essence of our invention to produce a display stand in which a few samples of each class of, say, baked goods, for instance, may be neatly arranged in a series of trays which are adapted to be elevated into almost a vertical plane, whereby the entire line is instantly placed before the view of the customer. These stands may be em-

ployed for every class of staples sold in a store, and when collapsed occupy but very little room upon the show case or counter. Yet, at the same time, the unique method of simultaneous display of an entire line, as effected by these stands, immediately attracts and rivets a possible purchaser's attention and produces a favorable impression.

Another valuable application of this stand is in the exposition of samples of suitings by tailors. At the present time a tailor possesses a number of cards containing samples of the various goods, from which it is often a hard matter for the customer to select. Then follows a trip around the shop examining the various styles in the bolt. All this requires time and must be figured in the selling cost of the goods. With our stand, however, it is simply necessary to place the same upon a low elevation properly arranged before a mirror and the stand wholly elevated. In each of the trays are contained all of the patterns of a particular fabric, each sample large enough for proper display. All the shades and designs of the various fabrics being thus simultaneously displayed and reflected by the mirror, it is much easier for the potential purchaser to make a comparison and selection; resulting in a quicker sale.

Traveling men visiting the wholesaler will also find this stand of great advantage, inasmuch as it can easily be inserted into a telescope case; as quickly extracted therefrom, and with one movement of the hand the entire line may be placed before the purchasing agent.

The essential feature of our invention resides in means whereby an entire row of connected, horizontally arranged, superimposed trays which, when in collapsed position, may, by a single lift of the hand, be elevated to, and disposed in a practically vertical plane, and when so elevated, will be automatically locked in such position. And included in aforesaid means, are co-related devices whereby another slight lift of the hands will break such lock and permit the trays to collapse by gravity.

To better understand our invention, reference is now made to Figs. 1, 2 and 3 which discloses the preferred mode of construction, in which A represents the base of our structure, which base may be a solid block of wood neatly beaded along its perpendicular

edges to present a pleasing finish, or which may be in the form of a tray, Fig. 1, for the reception of advertising literature descriptive of the goods displayed. Directly superimposed upon said base when our device is collapsed, are any desired number of trays B. C. D. E. F., etc. Fixed to tray F on both ends thereof, near their upper edges, are narrow, metallic bars 1; similarly attached to trays E. D. and C are bars 2, 3, and 4, the difference between the said bars and bar 1 being that the first named extend practically the entire width of their respective trays while the last indicated extends only a short distance beyond the transverse center of tray F as clearly seen in Figs. 1, 2 and 3. All of said bars are fastened to their respective trays at points equidistant from the transverse medial point by rivets 5, so that a perpendicular drawn through one of the rivets will pass through all in that particular series. Fixed to the base or tray A are similar bars 6, which are offset at one end as at 7 to form open jaws 8 between said bars 6 and the ends of tray or base A.

Attached to tray B in position similar to the others are bars 9 provided at one free end with right angled downwardly pending projections 10 which fit into the jaws 8 and are pivoted therein by rivets or studs 11. Pivoted to the forward end of bars 1 of tray F, to the longitudinal center of bars 2 of tray E, and to the rear ends of bars 3 of tray D, are floating links 12. Connected in a similar manner to the front end of bars 2, center of bars 3, and rear ends of bars 4, are like links 13; and likewise connected to the front ends of bars 3, center of bars 4, and rear ends of bars 9 are links 14. Connected to the front end of bar 4 and center of bar 9 are links 15. Connected to the center of bars 1 and rear ends of bars 2 are links 12^a, the whole producing lazytongs L located adjacent and attached to both ends, respectively, of the trays B. C. D. E. and F.

Referring now to the last and lowest connecting links 15, it will be observed that they are only connected to the front ends of bars 4 and to the center of bars 9. Beyond the pivotal points on said bars 9, said links have right-angled, upwardly extending projections 15^a, to the free ends of which are pivoted forwardly declined links 16, which links are offset at 17 to reach over horizontal bars 18 on base A, and are pivoted thereto at 19. It is now to be noted that the plural has been employed in referring to the various links and bars, the reason of this being that the parts at the opposite ends of the trays are true duplicates of each other, both individually and as assembled mechanism.

The process of extending our device into display position may now be described as

follows: Assuming the stand in the collapsed position, as in Fig. 2, all that is required is to lift up on tray F, when all the others will follow, due to the floating connecting links therebetween, the motion being that of the usual lazytongs. But, the last named, lowest link 15 having the freely, oscillating, right angled projection 15^a connected to bars 18 on the tray A by links 16, will cause the tray B to rotate about the pivots 11 until the joints or pivots 19, 20 and 21 are in direct alinement, when a perfect toggle lock is produced, which retains the trays B. C. D. E. and F in a relatively perpendicular plane or in what is known as the display position. In order to collapse the trays a slight forward pressure is applied at K, Fig. 1 to swing the tray F forward sufficiently to break the aforementioned toggle-lock, whereupon the trays will easily return to their collapsed position.

While herein we have disclosed the preferred mode of practising our invention, we reserve the right to make such changes and alterations as might suggest themselves to the skilled mechanic or permitted under the doctrine of mechanical equivalents.

Having thus fully disclosed our invention, we claim as new and desire to secure to ourselves by Letters Patent of the United States:—

1. A display stand including a base and a series of display containers normally superimposed thereon, lazytongs adjacent the opposite ends of said containers, which ends are connected to members of said lazytongs, the lowermost member of each of said tongs being hingedly connected to said base and the next to lowermost members pivoted to said lowermost members, the free ends of the said next to lowermost members being link connected to said base, whereby when said lazytongs are being extended, said tongs and their connected display members are caused to swing around said hinges on said base into a practically perpendicular plane and locked there against collapse.

2. A display stand including a base and a series of display containers normally superimposed thereupon, lazytongs connected to each of said containers at the opposite ends thereof, the lowermost members of which lazytongs are hinged to said base, links pivoted to said base and to the next-to-lowermost members of said tongs, whereby when said containers are elevated, toggle locks are formed by said links and next-to-lowermost members, preventing the collapse of said tongs.

3. A display stand including a base and a series of normally, horizontally disposed display containers superimposed thereupon, lazytongs comprising a plurality of pivotally connected members attached to and supporting said containers at the opposite

ends thereof, the lowermost members of which lazytongs are hinged to said base, and means connecting the next-to-lowermost members of said tongs and said base, whereby 5 when said tongs are extended, the same and said containers are forced into an essentially vertical plane and locked there against collapse.

4. A display stand including a base and 10 a series of normally, horizontally disposed display containers superimposed thereupon, lazytongs comprising a plurality of pivotally connected members attached to and supporting said containers at the opposite ends 15 thereof, the lowermost members of which lazytongs are provided with depending extensions hinged to said base, next-to-lower-

most members of said tongs, said members having right-angled extensions at their free ends, links connecting said extensions and 20 said base, whereby when said tongs and said containers are elevated, toggle locks are formed by said links and said next-to-lowermost members, preventing the collapse of said tongs.

25

In testimony whereof we have hereunto set our hands in the presence of two subscribing witnesses.

WILLIAM SCHWEITZER.
